(57) **CLAIM**

The ornamental design for a motorcycle footrest, as shown
and described.

DESCRIPTION

FIG. 1 is a perspective view of a motorcycle footrest of the
present invention showing my new design;

FIG. 2 is a front elevational view of the motorcycle footrest
of FIG. 1;

FIG. 3 is a right side elevational view of the motorcycle
footrest of FIG. 1, the left side being a mirror image thereof;

FIG. 4 is a top plan view of the motorcycle footrest of FIG.
1; and,

FIG. 5 is a bottom plan view of the motorcycle footrest of
FIG. 1.

Broken line representations in the drawings do not form a
part of the claimed design.
